UNITED STATES PATENT OFFICE.

CLARENCE L. JACKSON, OF SANDUSKY, OHIO, ASSIGNOR TO HENRY C. WAGNER, OF SANDUSKY, OHIO.

PACKET-TYING DEVICE.

No. 895,403.

Specification of Letters Patent.

Patented Aug. 4, 1908.

Application filed October 8, 1907. Serial No. 395,711.

To all whom it may concern:

Be it known that I, CLARENCE L. JACKSON, a citizen of the United States, residing at Sandusky, in the county of Erie and State of Ohio, have invented certain new and useful Improvements in Packet-Tying Devices, of which the following is a specification, reference being had to the accompanying drawings.

- 10 My invention relates to improvements in packet ties or holders and consists of the novel construction and the combination and arrangement of parts hereinafter described and claimed.
- 15 The object of the invention is to provide a device of this character which will be simple, strong, durable and inexpensive in construction and one which may be quickly and easily manipulated to fasten or unfasten a packet 20 or the like.

The above and other objects, which will appear as the nature of the invention is better understood, are attained in the preferred embodiment illustrated in the drawings, in 25 which

Figure 1 is a perspective view of a package showing the same fastened by my improved tying or holding device; Fig. 2 is a perspective of the base board or plate; and Fig. 3 is a 30 longitudinal section through the device.

My improved package tie or holder comprises a base board or plate 1 on which are two superposed clamping disks 2, 3, and a cord or similar flexible element 4. The base 35 board or plate is here shown as of rectangular shape and is formed with two apertures 5, 6 which are arranged opposite the center of adjacent right angularly disposed edges of the plate and are adapted to receive the cord 40 4, as clearly shown in Fig. 2. By arranging the apertures in this manner and passing the cord therethrough as shown, it will be seen that the cord will be slidably attached to the plate and that its ends will project from the 45 plate in planes at right angles to each other so that one may be passed around the package or bundle in one direction and the other around it in a direction at right angles. While said apertures are preferably arranged 50 opposite the center of adjacent side and end edges of the rectangular plate 1, it will be understood that they may be otherwise located and that when the plate is made of other than rectangular shape said apertures will be 55 arranged so that the ends of the cord can pro-

ject in planes at right angles to each other. The two disks are secured centrally upon the base plate and concentrically with each other by a rivet 7 having a flat circular head 8 at one end and a tubular shank at its opposite end. This rivet also passes through a spacing washer 9 arranged between the two disks, a spacing washer 10 arranged between the large lower disk and the base plate and a washer 11 arranged upon the bottom face of the base plate. The portion of the shank of the rivet projecting through the washer 11 is expanded or upset as shown at 12 to effectively clamp the several parts of the device together. The superposed disks and base 60 plate may be constructed of heavy cardboard, metal or any other sheet material that is resilient or flexible so that the ends of the cord 4 will be effectively clamped when wound around either of the washers 9, 10 and 70 75 between said disks and the base plate.

In using the device the base plate is placed upon the center of one side of the package as shown in Fig. 1 and one end of the cord is passed longitudinally around the package 80 and then wound one or more times around the washer 10 between the lower, larger disk and the base plate, and the other end of the cord is then passed around the package side- 85 wise or transversely and wound one or more times around the washer 9 between the two disks. By arranging the cord in the base plate so that both of its ends project and can be passed in planes substantially at right angles around the package and by providing 90 the two superposed disks upon the base plate, one disk to receive one end of the cord beneath it and the other disk to receive the other end of the same, it will be seen that one end of the cord may be loosened or untied 95 without disturbing the other end and consequently access may be had to one side or end of the package without entirely removing the fastening device. A further advantage of this construction is that the relative 100 length of the ends of the cord may be varied according to the relative length and width of the particular package to be fastened by the device. This adjustment of the length 105 of the ends of the cord is effected by sliding it through the apertures 5, 6 in the proper direction when the device is removed from the package. It will be further noted that the construction of the device is exceedingly 110 simple so that it can be produced at a small 115

cost and enables the device to be quickly and easily applied or removed.

Having thus described my invention what I claim is:

- 5 A packet tie or holder comprising a rectangular base plate formed with apertures arranged opposite adjacent side and end edges of said plate, superposed disks arranged centrally upon the plate and concentrically with 10 each other, the upper disk being of less diameter than the lower one, a spacing washer between said disks, a spacing washer be-

tween the lower disk and the base plate, a fastening passed through said disks, said washers and the base plate and a cord passed through said apertures in the base plate and having its ends projecting, substantially as and for the purpose set forth.

In testimony whereof I hereunto affix my signature in the presence of two witnesses. 20

CLARENCE L. JACKSON.
